(57) **CLAIM**

The ornamental design for a float body for intravenous infusion set, as shown and described.

DESCRIPTION

FIG. 1 is a perspective view showing my new design for a float body for intravenous infusion set;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof, the broken line showing the float body for intravenous infusion set in FIG. 7 forms no part of the claimed design; and,

FIG. 8 and FIG. 9 are perspective views of the float body for intravenous infusion set of this invention using in two types of flow regulator, the broken line showing the float body for intravenous infusion set in FIGS. 8 and 9 forms no part of the claimed design.
